UNITED STATES PATENT OFFICE.

LOUIS E. SHAW, OF EAST ORANGE, NEW JERSEY.

RADIODIAL.

Application filed April 30, 1925. Serial No. 26,931.

The invention relates to a one piece molded dial knob of the type commonly employed on electric instruments for manually adjusting variometers, variable condensers, 5 rheostats, and the like.

Such dials are commonly formed with a central knob portion usually knurled for digital manipulation and which knob portion merges into an outwardly extending 10 flange portion provided with a semi-circular line of graduations and with corresponding numeral designations.

The present disclosure distinguishes over known forms of such dials in that the diameter of the manipulating knob portion is 15 made quite large compared to the all over diameter of the unit so as to feature a more sensitive control than has been possible heretofore with the relatively small size knob portion. In hollow dials of the type under 20 discussion it has been regarded as necessary to provide reinforcing webs between the usual centrally positioned mounting hub and the side wall of the knob portion, even 25 in cases where the internal diameter of the knob was less than the unusually large size herein featured. In a new form of vernier condenser invented by applicant it is proposed to mount certain mechanisms within 30 the annular space provided within the knob portion and, therefore, the usual spider form of reinforcement could not be used.

Accordingly, the primary object of the invention is to provide a molded dial knob, 35 the knurled hollow knob portion of which could be made of unusually large dimensions; which would be free of internal reinforcement and other projections extending into the annular space between the hub and 40 the outlining wall of the knob, and which at the same time could be made of the usual moldable material with the major part extremely thin in cross section and which at 45 the same time would be of sufficient rigidity to withstand the usage to which such dials are subjected.

Broadly these objects are attained by molding the dial knob with the desired large size and hollow configuration provided care 50 be exercised that the major part of the molded structure be of uniform thickness and that the periphery adjacent its extreme edge be slightly thickened to provide an outlining reinforcement.

55 Another object of the invention, and featuring economy in manufacturing cost, is

the providing of a metal insert sleeve in the central hub and which sleeve is secured in position as an incident of the molding process in forming the article. 60

The invention also features the providing of a set screw for securing the molded article to its mounting shaft, and which screw is mounted in a molded part of the hub in order to facilitate guiding of the screw in 65 its clamping position engaging the mounting shaft or rod.

Various other objects and advantages of the invention will be in part obvious from an inspection of the accompanying drawings 70 and in part will be more fully set forth in the following particular description of one form of device embodying my invention, and the invention also consists in certain new and novel features of construction and combination of parts hereinafter set forth and claimed. 75

In the accompanying drawings:—

Figure 1 is a view in axial cross section through a preferred embodiment of the invention; and 80

Figure 2 is a view in rear elevation looking at the face of the dial from the right hand side of Figure 1. 85

In the following description and in the claims, parts will be identified by specific names for convenience of expression but they are intended to be as generic in their application to similar parts as the art will permit. 90

The dial is formed largely of a one-piece molded construction of bakelite or other material usually used in such constructions and comprises a substantially flat frusto-conical hollow knob portion 10, having a closed front wall 11 of slightly convexed form. A flange portion 12 extends outwardly and integrally from the edge of the knob portion, and is of relatively small width compared to the diameter of the knob portion 10. The front and rear faces 13 and 14 of this flange extend parallel to each other and perpendicular to the axis of rotation of the disk indicated by the lines *a—b* in Figure 1. The front face 13 of this flange is particularly designed to contain the graduation numerals, or other characters intended to be read from the front side of the dial. 95 100 105

The flange portion 12 is outlined by a dial rim 15, the rear face 16 of which extends parallel to and is offset slightly rearwardly from the rear face 14 of flange portion 12. 110

The front face of the dial rim is beveled, as shown in 17, and meets the rear face 16 at a sharp edge 18. The radial width from the inner to the outer edge of the face 16 is materially greater than the thickness of the knob portion and of the flange portion 12 so that the rim is of greater thickness than the other portions of the knob and thus provides a marginal reinforcement for the unit as a whole. This increase in thickness of the rim is provided by beveling the inner face 19 of the dial rim at a sharper angle to the plane of the flange portion 12 than the front face 17. It is a feature of this disclosure that the external diameter of the knob portion considered in the plane of the face 13 is greater than the radius of the entire knob. In other words, the knob has a diameter greater than one-half of the diameter of the dial rim.

It is particularly noted that except for this dial rim the flange portion and the knob portion are of substantially uniform thickness and in actual practice the parts are made thinner, and therefore cheaper, than similar constructions now on the market.

Projecting integrally from the center of the wall 11 and extending into the hollow knob portion is a substantially cylindrical hub 20 somewhat resembling conventional forms, and this part of the device also resembles conventional forms in that an open end metal insert sleeve 21 is mounted centrally in the hub. The construction distinguishes from conventional forms in that the sleeve is reduced in external diameter at its inner end to form a shoulder 22. The shoulder is locked by a ring 23 formed integral with the hub during the process of molding the article. The ring overlaps the shoulder and thus provides an interlocking means for securing the sleeve permanently in preset position in the hub.

A molded projection 24 extends laterally from one side of the hub to form a screw post for receiving a set screw 28 extending therethrough perpendicular to the axis *a—b*. The metal sleeve is provided with a tapped aperture 26 to receive the screw carried by the post. In the illustrated showing the post is also tapped after the molding process to receive the screw but it is optional

whether the screw engages either or both the sleeve and molded post. Access is provided to the screw head through opening 27 in the side of the knob portion.

In the illustrated showing the side of the hub portion is roughened or knurled to facilitate engagement therewith by the operator's fingers and this roughening extends not only along the side of the knob portion, but also over a projecting rib 28 outlining the convexed wall 11 so as to provide an extensive surface for facilitating engagement of the device at its front side as well as on the frusto-conical side of the knob.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. A one-piece molded dial knob comprising a substantially flat circular plate forming a flange portion, a hollow knob portion positioned centrally of the plate having its edges merging integrally into the plate, said hollow knob portion providing therein a clear annular space for accommodating contained mechanisms, said knob and said plate being substantially of uniform thickness, a bevel faced dial rim outlining said flange portion, and said knob having a diameter in the plane of the top of the plate greater than the maximum radius of the plate and rim, said rim having a thickness greater than the thickness of the flange to provide a strengthened peripheral edge to the flange.

2. A molded dial knob including a frusto-conical hollow knob portion, a slightly convexed wall closing one end, a rim outlining the convexed wall, the side of said knob portion and said rim being knurled to provide roughened surface to the side and front of the knob.

Signed at New York, in the county of New York and State of New York, this 29th day of April A. D. 1925.

LOUIS E. SHAW.
